UNITED STATES PATENT OFFICE.

FRANK MIENTUS, OF OLIVER, PENNSYLVANIA.

RAILWAY-SWITCH.

1,087,034.

Specification of Letters Patent. Patented Feb. 10, 1914.

Application filed October 8, 1913. Serial No. 793,210.

To all whom it may concern:

Be it known that I, FRANK MIENTUS, a citizen of the United States, residing at Oliver, in the county of Fayette and State 5 of Pennsylvania, have invented new and useful Improvements in Railway-Switches, of which the following is a specification.

This invention relates to improvements in automatic railway switches and has particular application to a switch of the class described for use in mines. It is to be understood, however, that the invention in its useful application is not limited to this particular purpose as the same may be employed in 15 conjunction with street railways and the like.

In carrying out the present invention, it is my purpose to provide a railway switch wherein the switch points may be thrown 20 from one position to the other by the operator on the car while the latter is in motion thereby eliminating the necessity of stopping the car and subsequently throwing the switch.

It is also my purpose to provide an automatic railway switch which will embrace the desired features of simplicity, efficiency and durability, one which may be installed and maintained at a minimum expense and one 30 wherein the component parts will be so arranged and correlated as to reduce the possibility of derangement or breakage to a minimum.

With the above and other objects in view, 35 the invention consists in the construction, combination and arrangement of parts hereinafter set forth in and falling within the scope of the claims.

In the accompanying drawings; Figure 40 1 is a cross sectional view through a trackway, showing a car thereon in elevation. Fig. 2 is a top plan view of the trackway. Fig. 3 is an enlarged cross sectional view therethrough. Fig. 4 is an enlarged perspective view of one of the switch points removed from the track. Fig. 5 is a fragmentary side elevation of the car showing the operating devices carried thereby. Fig. 6 is an enlarged perspective view of one of 45 the operating devices removed from the car body.

Referring now to the accompanying drawings in detail, 1, 1 designate the main line rails, while 2, 2 indicate the rails of the 55 siding or branch line, the pivoted switch points being shown at 3 and capable of

movement to control traffic from the main line to the siding or branch line. These switch points are interconnected through the medium of a rod 4 for simultaneous movement and fastened to the confronting sides of the switch points at the free ends thereof are shoes 5 having the inner surfaces convexed as at 6.

The numeral 7 designates a bearing block 65 suitably fastened to one of the ties and arranged between the rails of the main line and formed with a recess 8 in the upper surface thereof. A switch throwing bar 9 is pivoted between its ends upon a pivot bolt 10 passed through the recess 8 in the block 7 and is capable of swinging movement about the pivot bolt and has the opposite ends thereof rounded off as at 11 to engage the convexed faces 6 of the shoes 5, 5. Thus, 70 when the bar 9 is swung about the pivot bolt 10 in one direction one end 11 thereof will engage the adjacent shoe 5 to swing the switch points in one direction, while when the bar is swung in the opposite direction the opposite end thereof will engage 75 the respective shoe and so throw the switch points in the reverse direction.

In order that the switch throwing bar 9 will be kept clear of the ground so that the 80 same may swing freely about its axis, the under surface of the bar is formed with a recess 12 disposed above the recess 8 in the bearing block 7, while interposed between the opposite walls of such recesses 12 and 85 8 and encircling the pivot bolt 10 is a coiled expansion spring 13 having one end bearing upon the lower wall of the recess 8 and the opposite end in engagement with the top wall of the recess 12, such spring acting normally to hold the bar 9 elevated.

Arranged between the lines of rails and upon one side of the bar 9 is a stop block 14 suitably fastened to the tie, while arranged below the opposite ends of the bar 9 are shoes 15 adapted to be engaged by the under surface of the switch throwing bar in the event of pressure being applied to the upper surface thereof so as to prevent mutilation of the pivot bolt and the bar.

In the present instance, the car carried mechanism for operating the switch throwing bar 9 whereby the switch points may be thrown to the desired position so that traffic may continue over the main line or pass 110 from the main line onto the siding as the case might be, comprises blocks 16 fastened

to the lower surfaces of the car bolsters at the corners of the car and having the under surfaces thereof convexed as at 17 and adapted to engage the convexed upper surfaces 18 of blocks 19 suitably fastened to the upper surface of the switch throwing bar 9 and disposed at the opposite sides of the pivot bolt.

The form of my invention illustrated in the accompanying drawings is particularly adapted for use in coal mines and in practice the forward block 16 on one side of a loaded car approaching the switch contacts with the convexed surface 18 of one of the blocks 19 on the switch throwing bar and so swings the latter in one direction to throw the switch points whereby the car will take the proper path. The forward block at the opposite side of a following car contacts with the other block 19 and so throws the switch throwing bar 9 in the reverse direction so that the last-mentioned car proceeds along the trackway opposite that traversed by the first car. Thus, it will be seen that succeeding cars are switched in opposite directions automatically thereby eliminating the necessity of "kicking" the switch points.

I claim:

1. In a railway switch, the combination with the switch points, of shoes fastened to the free ends of said points on the inner sides thereof, a bar pivoted centrally and between said shoes, and means for swinging said bar whereby either end thereof may be brought into engagement with the adjacent shoe to throw the switch points to the desired position.

2. In a railway switch, the combination with the switch points, of shoes fastened to the free ends of said points on the inner sides thereof, a bar pivoted centrally and between said shoes, means for swinging said bar whereby either end thereof may be brought into engagement with the adjacent shoe to throw the switch points to the desired position, and means holding said bar elevated.

3. In a railway switch, the combination with the switch points, of shoes fastened to the free ends of said points on the inner sides thereof, a bar pivoted centrally and between said shoes, means for swinging said bar whereby either end thereof may be brought into engagement with the adjacent shoe to throw the switch points to the desired position, and a spring holding said bar elevated.

4. In a railway switch, the combination with the switch points, of shoes fastened to the free ends of said points on the inner sides thereof, a bar pivoted centrally and between said shoes, and blocks carried by the under surface of a car at the corners thereof and adapted to engage said bar to swing the same whereby either end thereof will be brought into engagement with the adjacent shoe to throw the switch points to the desired position.

In testimony whereof I affix my signature in presence of two witnesses.

FRANK MIENTUS.
